CLAIM

The ornamental design for a user interface with a light ring for a hearing protection device, as shown and described.

DESCRIPTION

FIG. 1 is a perspective view of a user interface with a light ring for a hearing protection device, showing our new design in an unused condition not lighted;

FIG. 2 is a front view thereof, shown in a used condition with the first panel lighted;

FIG. 3 is another front view thereof, shown in a used condition with the first and second panels lighted;

FIG. 4 is another front view thereof, shown in a used condition with the first, second and third panels lighted;

FIG. 5 is another front view thereof, shown in a used condition with all four panels lighted;

FIG. 6 is another front view thereof, shown in a used condition with only the fourth panel lighted;

FIG. 7 is another front view thereof, shown in a used condition with the third and fourth panels lighted;

FIG. 8 is another front view thereof, shown in a used condition with the second and third panels lighted; and,

FIG. 9 is another front view thereof, shown in a used condition with the first and fourth panels lighted.

The broken lines shown in the drawings are only provided to illustrate the environment of the design, and form no part of the claimed design.

The stipple shaded areas represent the illuminated panels of the light ring.
